UNITED STATES PATENT OFFICE.

ROBERT KANE, OF HUMBOLDT, ILLINOIS.

GEARING.

1,241,855.

Specification of Letters Patent.

Patented Oct. 2, 1917.

Application filed March 3, 1916. Serial No. 81,890.

To all whom it may concern:

Be it known that I, ROBERT KANE, a citizen of the United States, residing at Humboldt, in the county of Coles and State of Illinois, have invented certain new and useful Improvements in Gearing, of which the following is a specification.

This invention relates to improvements in gearing, more particularly to the gearing mechanism for actuating the dasher portions 10 of churning and the like, and has for one of its objects to simplify and improve the construction and increase the efficiency and utility of devices of this character.

Another object of the invention is to provide a mechanism which may be applied without material structural change to churn dasher devices of various forms and likewise to cream receptacles of various sizes and 20 forms.

Another object of the invention is to provide a simply constructed device whereby the requisite speed is accomplished by a mechanism which is actuated at a relatively 25 slow speed.

Another object of the invention is to provide a device including a casing having upper and lower members provided with vertically aligned shaft bearings and supporting a plurality of shafts which carry the operating gears, the casing members operating to maintain the shafts in position and prevent the disengagement of the gears.

With these and other objects in view, the 35 invention consists in certain novel features of construction, as hereinafter shown and described and then specifically pointed out in the claim; and in the drawings illustrative of the preferred embodiment of the invention—

Figure 1 is a sectional elevation of the improved device;

Fig. 2 is a transverse sectional elevation of the same;

Fig. 3 is a plan view with the cover or closure of the casing for the operating mechanism removed;

Fig. 4 is an enlarged perspective view of the coupling member between the dasher 50 rods and the operating mechanism.

Corresponding and like parts are referred to in the following description and indicated in all the views of the drawings by the same reference characters.

The improved device includes a support-

ing member, indicated as a whole at 10, and which is preferably the cover or top of the cream receptacle, the latter being indicated at 11. The receptacle 11 and the top 10 may be of any required form or size and it 60 is not desired, therefore, to limit the invention in this respect. Disposed upon the bottom of the receptacle 11 are steps 12 to receive the lower ends 13 of dasher rods 14, the latter being disposed in parallel relation 65 and provided with suitable blades 15 which are disposed at right angles to the dasher rods and coat when the dasher rods are rotated to produce the churning action. The blades or paddles 15 are arranged in alternating relation relative to each other, and when the dasher rods are rotated the blades of one rod will move between the blades of the other, as illustrated in Figs. 1 and 2.

Disposed above the closure portion 10 is a 75 casing represented as a whole at 16 and supported by suitable legs 17 from the member 10. The casing 16 is thus permanently connected to the member 10, and spaced above the same, as shown. The casing 10 is provided with a closure 18 secured thereto in any suitable manner, for instance by clamp bolts 19. Mounted for rotation through the bottom and top of the casing is a main drive shaft 20 which extends through a sleeve 21 80 on the cover 18 of the casing and adapted to receive an operating crank 22 at its upper end and externally of the casing. Mounted to rotate with the shaft 20 within the casing is a relatively large gear 23 which engages 85 with a pinion 24 upon another shaft 25 mounted for rotation in the casing and its cover. Mounted upon the shaft 25 within the casing is another gear wheel 26. Mounted for rotation in the bottom of the casing 90 16 and likewise in its cover 18 are shafts 27—28, and mounted upon these latter shafts are pinions 29—30. At their lower ends the shafts 27—28 are enlarged, as shown, the enlarged portions depending below the bottom of the casing or between the casing and the base member 10. The enlarged portions 31—32 are provided with sockets to receive the upper ends of the dasher rods 14, and are held in position by set screws 33—34. The 95 shafts 27—28 are provided respectively with flanges 35—36, which bear upon the inner face of the bottom of the casing 16, and thus prevent the downward displacement of the shafts. Preferably the shafts 27—28, to 100 110

gether with their enlargements and bearing flanges and pinions will be integral, or cast in one piece, preferably of steel, as illustrated in Fig. 4. It will thus be obvious 5 that when the parts are assembled, as shown in Figs. 1, 2 and 3, and rotary motion imparted to the shaft 20 by power applied to the crank 22, the dasher rods 14 will be very rapidly rotated by a relatively slow speed 10 applied to the crank.

The upper and lower casing members with 15 their vertically aligned shaft bearings support the shafts in position and prevent disengagement of the gears. The gears are thus held in constant operative position, and thus avoid any tendency to become separated during the operation. The supports 17 being disposed at the corners of the lower casing member are disposed in spaced relation 20 and distributed over the lower casing member, thus maintaining the latter in fixed relation to the support 10 and spaced constantly therefrom. By distributing the supports 17 as shown the casing is uniformly supported 25 and has no tendency to vibrate or be otherwise moved relative to the support 10.

The improved device is simple in construction, can be readily applied, and operates effectually for the purposes described.

30 The dasher members may be readily detached by simply loosening the set screws, to enable them to be cleansed or disinfected, and all parts which come in contact with the cream may be readily cleansed without

detaching or separating the operating mechanism.

Having thus described the invention, what is claimed as new is:—

In a device of the class described, a closed casing provided with depending attaching legs and having its bottom formed with transversely aligned openings, a cover detachably secured to the casing and provided with an upstanding bearing sleeve, a main shaft journaled in the bearing sleeve and in an opening in the bottom of the casing and provided with a master gear, a stub shaft spaced from the main shaft and journaled in the casing, said stub shaft being provided with a pinion meshing with the master gear, oppositely disposed counter-shafts arranged within the casing and having their upper ends provided with pinions and their lower ends enlarged and extended through the adjacent openings in the bottom of the casing and provided with sockets for the reception of dasher rods, said enlarged portions being formed with annular flanges disposed within the casing and resting on the bottom thereof, a relatively large gear wheel carried by the stub shaft and meshing with the pinions on the counter-shafts, and a hand crank secured to the main shaft above the bearing sleeve whereby when the hand crank is operated the dasher rods will be rotated 65 in the same direction.

In testimony whereof I affix my signature.
ROBERT KANE. [L. S.]
